UNITED STATES PATENT OFFICE.

LIZZIE DANDRIDGE, OF WICHITA, KANSAS.

WINDOW BARRIER.

Application filed September 15, 1926. Serial No. 135,631.

The present invention relates to an open-work barrier for windows or other openings in a building for preventing burglars or any other unauthorized persons from gaining access to a building, and aims to provide a novel and improved device of this character which may be conveniently removed from a window, or the like, in case of fire or for any other unknown reason, said device being so constructed as to permit disconnection thereof from the inside of the window only, thus preventing persons on the exterior of the building disconnecting the barrier from the window.

Another object of the invention is the provision of a shield carried by the lower portion of the barrier adapted to engage over a window sill, said shield extending downwardly of the sill and having on its undersurface locking means for retaining the barrier in place, the shield being so constructed as to prevent persons on the outside of the building reaching through the barrier and disconnecting said locking means.

A further object of the invention is to provide a bar hinged at one end to a window frame, while the opposite end is received in a bracket at the opposite side of the frame, and a flexible element connected to the free end of the bar with its opposite end detachably connected under the shield, said bar being arranged to aid in supporting the barrier in place against inward pressure on the barrier in order to force the same from the window frame.

It is also an object of the invention to provide a barrier of the above indicated character, which is simple and substantial in construction, which can be manufactured economically, and which will be thoroughly efficient and practical in use.

With the foregoing and other objects in view, which will be apparent as the description proceeds, the invention resides in the construction and arrangement of parts, as hereinafter described and claimed, it being understood that changes can be made within the scope of what is claimed, without departing from the spirit of the invention.

The invention is illustrated in the accompanying drawings, wherein:

Figure 1 is an interior view of a window frame, showing my improved barrier attached thereto,

Figure 2 is a vertical section taken on line 2-2 of Figure 1,

Figure 3 is a perspective view of the barrier removed from the window frame,

Figure 4 is a perspective view of a window frame showing the various means thereon for connecting the barrier thereto,

Figure 5 is a horizontal cross section taken on line 5-5 of Figure 1,

Figure 6 is a similar view taken on line 6-6 of Figure 1, and

Figure 7 is an elevation showing the top edge of the barrier and the means for connecting the top of the barrier to the window frame.

Referring to the drawings, the letter *a* indicates a window frame having the side facing plates *b*, sill *c*, and lower facing plate *d*, to which my improved window barrier is to be attached. In carrying out the invention, the numeral 10 designates a rectangular frame, constructed of side bars 11 and 12, top bar 13, and a shield plate 14 at its lower portion. The shield plate 14 has an upstanding flange 15 thereon which is secured by means of rivets or welding, as indicated at 16, to the side bars 11 and 12, while the top bar 13 is secured to the upper ends of the side bars 11 and 12 in a similar manner. The top bar 13 and the upstanding flange 15 of the shield both have their outer ends offset, as at 17, so that said bar 13 and flange 15 will have the surfaces thereof contacting with the window frame flush with the surfaces of the side bars 11 and 12.

Arranged approximately midway of the height of the frame 10 and having its opposite ends secured to the side bars 11 and 12 is a cross bar 18, which is offset throughout the major portion thereof intermediate its ends for a purpose which will be set forth as the description proceeds. Extending vertically with the side bars 11 and 12 and having their opposite ends secured to the upper bar 13 and the flange 15 is a series of spaced bars or ribs 19. The bars or ribs 19 have their edges extending inwardly and outwardly and their ends twisted, as at 20, adjacent the points where the same are secured to the upper bar 13 and flange 15 so as to present flat surfaces for engaging against the flat surfaces of the top bar 13 and flange 15. The bars or ribs 19 are secured intermediate their ends by means of welding or the like to the cross bar 18 so as to prevent flexing of the bars or ribs.

The upper ends of the side bars 11 and 12 are bent at right angles and extend out-

wardly away from each other, as at 21, so as to provide side extension plates having openings 22 therein which are adapted to receive upstanding prongs 23 carried by plate members 24 secured to the upper portion of the facing plates *b* of the window frame. The extension members 21 and prongs 23 form means for rigidly attaching the upper end of the barrier frame to the upper portion of the window frame.

The shield 14 has a horizontal surface 25 thereon which lies over the sill *c* of the window frame and a depending apron portion 26 which extends down over the lower facing plate *d*. On the inside of the apron 26 is secured a pair of eye members 27, said eye members being spaced sufficiently apart and a sufficient distance from the ends of the apron so as to eliminate the danger of a person on the outside of a building from reaching between the bars and under the apron to the eyes. On the lower facing plate *d* is secured a pair of hook members 28 which are adapted to be engaged in the eyes 27 on the apron for securing the lower portion of the barrier frame to the lower portion of the window frame.

Mounted on one of the facing plates *b* of the window frame approximately midway of its height is a bracket 29 which is hingedly connected to one end of a bar 30. On the opposite face plate of the window frame is a U-shaped bracket 31 which is adapted to receive the free end of the bar 30 so as to prevent further downward movement of the bar or side movement of the bar. Attached to the free end of the bar 30 is a chain 32 or any other suitable flexible element, which has in turn attached to its opposite end a hook 33 which is adapted to be engaged in an eye 34 also secured to the lower facing plate *d*. Extending outwardly from the shield 14 is a hook-shaped eye 35 through which the chain is adapted to be extended while passing downwardly to the eye 34 so as to retain the chain in proper position. The bar 30 is swung to the position indicated in Figure 1 after the barrier has been arranged in position. It can be seen that the bar 30 will aid in supporting the barrier frame so as to prevent inward pressure on the barrier frame for forcing the same away from the window frame.

When it is desired to attach the barrier frame to a window frame, the barrier frame is raised and the openings 22 in the extensions 21 arranged over the upstanding prongs 23. By then lowering the barrier frame and allowing the prongs 23 to extend into the eyes 22, the upper end of the barrier frame will be arranged in proper position. The lower end of the barrier frame is then swung towards the window frame so that the shield 14 extends over the window sill. By then engaging the hook members

28 into the eyes 27 on the inner surface of the apron 26 of the shield 14, the lower portion of the barrier frame will be secured in position. Then the bar 30 is swung downwardly until the free end thereof is engaged in the U-shaped bracket 31. By then engaging the hook 33 on the lower end of the chain 32 in the eye 34, the barrier frame will be locked in position. It can be seen that a person on the outside of the building cannot reach between the bars or ribs 19 and under the shield 14 to disengage the hooks 33 and 28 from the eyes 34 and 27. In case of fire, or for any other unknown reason, a person inside of the building may easily disconnect the barrier frame from the window so as to permit access through the window opening.

The device will not only be effective for preventing unauthorized persons entering through a window opening, but will also serve the purposes of preventing a person walking in his sleep from accidentally falling through the window frame, the device also preventing small children who are playing or climbing around a window from accidentally falling through the window frame. By providing the barrier at a window frame, a person sleeping in a room may feel at ease to open the windows without danger of being disturbed by unauthorized persons. Often a person sleeping in a room without a window barrier keeps the windows tightly closed because of fear, thus the room has no ventilation during the period the party is sleeping. With my improved device applied to a window frame, a person may feel at ease at all times.

The barrier lies flat against the window frame so as to permit the shade to be raised and lowered over the same without interfering with the efficiency of the shade. The barrier will prevent the shade from being blown outwardly while the sashes of the window are open, thus eliminating the danger of cracking the sash. It is to be noted that the window barrier does not extend entirely up to the top of the upper sash, so as to permit a small space open at the top of the frame. When my improved barrier is used upon windows elevated a sufficient height from the ground to eliminate the danger of unauthorized persons entering the same, the barrier frame need not extend upwardly past the upper portion of the lower sash. In such cases the barrier frame is not used as a burglar proof device but is only used for the purpose of preventing a person accidentally falling through the window frame.

Having thus described my invention, what I claim as new is:

1. In combination with a window frame of a barrier frame constructed of openwork having eyes at its upper end, prong members

- carried by the window frame for engaging into said eyes, a shield arranged on the lower portion of said barrier frame and extending below the window opening, and securing elements arranged under said shield for attaching the lower end of the barrier frame to the window frame, said securing elements preventing upward movement of the barrier frame for disengaging said prongs from said eyes.
2. In combination with a window frame of a barrier frame constructed of openwork, means on the upper end of the barrier frame for attaching the same to a window frame, a shield arranged on the lower portion of said barrier frame and extending below the window opening, and securing elements arranged under said shield for attaching the lower end of the barrier frame to the window frame.
3. In combination with a window frame of a barrier frame constructed of openwork, a shield arranged upon the lower portion of the barrier frame and extending below the window opening, securing elements arranged under said shield for securing the lower portion of the barrier frame to the window frame, a pivoted bar secured to the window frame and extending across the barrier frame, and means attached to said bar and secured under the shield for holding the bar across the barrier frame.
4. In combination with a window frame of a barrier frame constructed of openwork having eyes at its upper end, prong members carried by the window frame for engaging in said eyes, a shield member arranged on the lower portion of said barrier frame and extending below the window opening, securing elements arranged under the shield for attaching the lower end of the barrier frame to the window frame, a bar hingedly connected to the window frame and adapted to extend across the same and engage the barrier frame for supporting the same against inward pressure, and means attached to said bar and secured under said shield for holding said bar in position.
5. In combination with a window frame of a barrier frame constructed of openwork, means at the upper end of said barrier frame for attaching the same to a window frame, a shield member arranged at the lower end of the barrier frame having a horizontal portion for engaging over the sill of the window frame and a depending apron portion extending over the lower face plate of the frame, and means attached to the underside of said apron and to the lower face plate for attaching the lower end of the barrier frame to the window frame.
6. In combination with a window frame of a barrier frame constructed of openwork, means at the upper end of said barrier frame for attaching the same to a window frame, a shield member arranged at the lower end of the barrier frame having a horizontal portion for engaging over the sill of the window frame and a depending apron portion extending over the lower face plate of the frame, and means attached to the underside of said apron and to the lower face plate for attaching the lower end of the barrier frame to the window frame.
7. In combination with a window frame of a barrier frame constructed of a rectangular frame structure, and a series of vertically extending bars, extension plates carried by the upper end of said barrier frame and extending away from each other, upstanding prong members secured to the window frame and engaging said extension members, a shield arranged at the lower portion of said barrier frame, and means arranged under said shield for securing the lower portion of the barrier frame to the window frame.
8. In combination with a window frame of a barrier frame constructed of side bars, top cross bar, a shield member at the lower end of the frame having an upturned flange secured at its opposite ends to said side bars, and a series of vertical bars secured to the top cross bar and to the flange of said shield; means at the upper end of said barrier frame for attaching the same to the window frame, a depending apron carried by said shield member and extending below the window opening, and means arranged under said depending shield for attaching the lower portion of the barrier frame to the window frame.
9. In combination with a window frame of a barrier frame constructed of side bars, top cross bar, a shield member at the lower end of the frame having an upturned flange secured at its opposite ends to said side bars, and a series of vertical bars secured to the top cross bar and to the flange of said shield; means at the upper end of said barrier frame for attaching the same to the window frame, a depending apron carried by said shield member and extending below the window opening, means arranged under said depending shield for attaching the lower portion of the barrier frame to the window frame, a bar hingedly connected at one end to one side of the window frame, a U-shaped bracket secured to the window frame at the opposite side where said bar is hinged for receiving the free end of said bar, a chain attached to the free end of said bar, and means arranged under the shield for detachably connecting said chain.
10. In combination with a window frame of a barrier frame constructed of side bars,

top cross bar, a shield member at the lower end of the frame having an upturned flange secured at its opposite ends to said side bars, and a series of vertical bars secured to the top cross bar and to the flange of said shield; means at the upper end of said barrier frame for attaching the same to the window frame, a depending apron carried by said shield member and extending below the window opening, means arranged under said depending shield for attaching the lower portion of the barrier frame to the window frame,

a bar hingedly connected at one end to one side of the window frame, a U-shaped bracket secured to the window frame at the opposite side where said bar is hinged for receiving the free end of said bar, a chain attached to the free end of said bar, a guide for said chain carried by said shield, and means arranged under said shield for attaching said chain.

In testimony whereof, I have affixed my signature.

LIZZIE DANDRIDGE.
